J. BENTZ.
MACHINE FOR FRAMING MATCH SPLINTS.
No. 68,342. Patented Sept. 3, 1867.

United States Patent Office

JACOB BENTZ, OF BROOKLYN, NEW YORK

Letters Patent No. 68,342, dated September 3, 1867.

IMPROVED MACHINE FOR FRAMING MATCH-SPLINTS.

The Schedule referred to in these Letters Patent and making part of the same.

TO ALL WHOM IT MAY CONCERN:

Be it known that I, JACOB BENTZ, of the city of Brooklyn, in the county of Kings, and State of New York, have made certain new and useful Improvements in Machines for Framing Match-Splints for Dipping; and I do hereby declare that the following is a full, clear, and exact description of the construction and operation of the same, reference being had to the annexed drawings, making part of this specification, in which—

Figure 1 represents a front view of my improved machine; the position on the right-hand side being shown bisected to exhibit some of its working parts.

Figure 2 is a vertical longitudinal central section of the same.

Figure 3 is a top view of the same, the rear being shown removed.

Figure 4 is a detached side view of the working parts used for operating the feed.

Figure 5 is a detached perspective view of one side of the grooved bed, the plunger-frame or comb and the working parts used for operating the feed of the splint-clamps or slats into the machine.

Similar letters of reference indicate corresponding parts in the several figures.

The improvements herein shown appertain or relate more particularly to a machine for framing match-splints, patented by me June 26, 1866; and the first part of my invention consists in the employment of a device for feeding the splint-slats into the machine as they are required for being filled with splints; the second part of my improvement consists in providing the cam-bar plunger-frame with cams on each side, and having double-acting levers attached to the machine, which are connected with the said feeding device, whereby an automatic feed of the splint-clamps or slats into the machine is obtained with a harmonious and positive action of and with the operation of the machine; the third part of my improvement consists in providing the grooved bed, which is used to separate and receive the splints from the hopper into its grooves, with a vertical slot or opening near the forward part, along the inside of the hopper and across all of the grooves, whereby broken splints, or splints lying across the grooves of the bed, are allowed to escape or are made to discharge through said opening from under the hopper, while and with the operation of and without stopping the machine.

To enable others skilled in the art to make and use my improvement, I will proceed to describe the construction and operation of the same.

The hoppers A, with the loose hopper B, shown in figs. 2 and 3, are made to vibrate over the grooved bed C to fill the grooves D of the grooved bed with splints, from whence the said splints are delivered by means of the plungers or comb D E passing through the grooves D of the said bed and thrust upon or into the grooves of the splint-slat F in front of the said bed. The slide G stops successively for every stroke of the plungers and receives a new charge of splints. All the above is made and operated in a similar manner to that shown by me in my former machines, but now, instead of furnishing the splint-clamps or slats one at a time upon the slide G, until a splint-frame is filled and completed, and thus made ready for dipping, I employ two vertical guide-posts H H, secured to the frame of the machine, above, on each side of, and in line with the slide G, each of which guide-posts is furnished with a vertical groove, I, of proper dimensions to guide and allow the ends of the splint-clamps or slats to pass or drop freely through said groove I down upon slide G. In the upper part of the groove I, in each post H, is hinged a friction-pawl, J, and a pawl, K, is located in its rear, hung on the same fulcrum, and arranged on the outside of the post H. The end of this pawl K is parted in two and bent at right angles so as to project and touch upon the rear end of the said pawl J, and is pressed upon said pawl by means of a spring, L, secured on the outside of the post H, so that when the splint-clamps are placed in the grooves I I the same are held from dropping down by means of the friction caused on their ends in passing the pawls J J, one each side of the posts H H. A third pawl, M, is hinged to the outside of the lower part of each post H, the end of which projects upward to within a distance equal to the thickness of the splint-clamps of the ends of the pawls J and K, and is bent over to project also a short distance into the groove I through a slot, N, made in the post H for the purpose of arresting the splint-clamps when dropped into it. A spring, O, presses upon the rear of this pawl M. Now, between the ends of these pawls K and M, in each post, is arranged, in proper bearings, a horizontal rock-shaft, P, provided with two short radial arms p and p', which radial arms are opposite each other, in such a manner that by the vibration of the rock-shaft P in one direction the arm p engages the pawl M and draws its end from projecting into the groove I, and by its vibration in an opposite direction the arm p' engages

the pawl K and withdraws the latter from pressing on the friction-pawl J. Each of the rock-shafts P P is provided with a crank on its outside end, and in order to transmit motion to the said rock-shaft P from the moving parts of the machine I employ a bent lever, R, on each side of the machine, having its central fulcrum r fixed in the frame, and provide each of the corresponding sides of the plunger-frame with a cam, S, shown in figs. 4 and 5, so that at each end of the motion of the plungers or comb E, the said cam S is brought in contact with one of the ends of the lever R, whereby the said lever is vibrated; and by means of an adjustable connecting-rod, T, pivoted to the crank Q and the rock-shaft P, and pivoted also to the outer end of the lever R, the said vibratory motion is transferred from the plunger-frame to the rock-shaft P.

When the machine is in operation a number of splint-clamps are placed horizontally between the guide-posts H H and inserted in the top of the grooves I I, and the same are arrested upon the projections of the pawls M M. As soon as the plunger-frame and plungers are nearly being pressed back to the end of its back motion the cams S S operate upon the inner end of the levers R R and the arm p' P' of the rock-shaft P P, releasing the pawls K K, whereby the pawls J J are forced to clamp the splint-slats, which is next to the lowest, while at the same time the arms p' P' of the said rock-shafts operate against the pawls M M and withdraw their projections, and the rests of the lowest splint-clamp or slat are withdrawn thereby, and in consequence the said splint-clamp drops down upon the top of the splint-clamp, which rests upon the slide G, as shown in figs. 1 and 2, the said slide having been lowered in the usual way by the same back motion of the plunger-frame. On the return or forward motion of the plunger-frame the cams S S come again in contact with the levers R R at their outer ends, and move the same back to their former position, whereby the pawls M M are made to project into the grooves I I, and the pressure upon the pawls J J is withdrawn, whereby the whole of the splint-clamps above drop and rest upon the projections of the pawls M M until the lowest of them is again delivered upon the slide G by the same operation of the backward motion of the plunger-frame as before described. Instead of having a portion of the grooved bed C hinged or parted to allow the escape of broken splints, or splints interfering with the proper operation of filling the grooves of the same from time to time, I employ one complete solid bed, which is provided with a narrow slot, U, cut through it, and extending across its grooves under the forward part of the hoppers immediately behind the usual scraper V on the forward lower edge of the loose hopper B, as shown in figs. 2, 3, and 5. By means of this slot U a proper and continuous escape for broken splints, or splints interfering with the proper filling of the said grooves in the bed C, is readily obtained by operating the hoppers and plungers, whereby the operation of the machine is considerably facilitated, and is rendered continuous.

What I claim as my invention, and desire to secure by Letters Patent, is—

1. The employment of a splint-clamp feeding device, arranged to work in connection with the machine for framing and filling the splint-clamps with splints, substantially as and for the purpose herein shown.
2. The employment of the cams S S, the levers R R, and connecting-rods T T, for the purpose of automatically operating the said feeding device, with the operation of the framing and filling of the splint-frames, substantially as herein shown.
3. The employment of the slot U, in connection with the grooved bed C and hopper B and plungers or comb E, substantially as and for the purpose herein described.

JACOB BENTZ.
